UNITED STATES PATENT OFFICE

NED C. L. BROWN, OF SCOTTSVILLE, NEW YORK, ASSIGNOR TO GENERAL RAILWAY SIGNAL COMPANY, OF ROCHESTER, NEW YORK

CAR-RETARDER SYSTEM

Application filed February 14, 1927. Serial No. 168,033.

This invention relates in general to railway car brake apparatus, and has more particular reference to braking apparatus of the type located along the track for retarding railway

line portions, connected by a vertical portion. In other words, the brake shoe pressure curve comprises two distinct zones, a low pressure, and a high pressure, zone.

5 cars by frictional engagement of the sides of the car wheels with spring pressed brake shoes.

Further objects, purposes, and characteristic features of this invention will appear as the description progresses, reference being had to the accompanying drawings, showing solely by way of example, one form of the invention. In the drawings:—

In the operation of retarders of this type it has been found desirable to vary the pressure of the brake shoes, and hence the braking effect, to correspond with the weight of the car to be retarded but if the pressure be too great for a particular weight of car the car wheels tend to rise up from between the shoes 15 and ride on top thereof. This matter has been more thoroughly discussed hereinafter and in the co-pending application Ser. No. 70,599, filed November 21, 1925, to which attention is directed.

Fig. 1 is a plan view of a portion of a car retarder constructed in accordance with this invention;

20 In practice, there is sometimes a variation in the thickness of the car wheels, and since the pressure exerted by the brake shoes in this type of brake depends on the relative position of the brake shoes and their actuating means, it is obvious that thicker wheels 25 will receive a greater braking effort than do thinner wheels, for a given setting of the braking apparatus, and thus disturb the proper proportioning of the brake shoe pressure relative to the weight of the car to be retarded.

Fig. 2 is a sectional elevation on line 2—2 of Fig. 1;

Fig. 3 is a fragmentary sectional view, to a large scale, of the compound springs and associated parts used in the invention; and

Fig. 4, 5 and 6 are diagrammatic views showing pressure-movement curves for the 70 brake shoes.

In general, the construction and arrangement of the parts of the car retarder shown in the drawings are the same as in the above referred to co-pending application Ser. No. 70,599, and accordingly the following description of such parts, although complete, will be very brief, and for a more detailed explanation reference may be had to such application.

80 Referring to Fig. 1, a track formed by rails 1, is equipped with a retarder system comprising brake shoes 2 on each side of each rail, the brake shoes being carried by brake bars 3 formed of articulated sections 3¹ 3² etc.

85 The brake bars or beams 3 are connected, by means to be described in detail below, to lugs 4' and 5' carried respectively by girder beams or actuating bars 4 and 5 arranged side by side in pairs, and operable in opposite 90 directions, at right angles to the track rails 1, by means of double angle levers 6, pivoted at 7 to fixed supports, and pivoted at 8 and 9 to the members 4 and 5. The levers 6 are pivotally connected to a bar 10 arranged to be reciprocated, through rod 11 and lever 12, by means of a reciprocating pitman 13, operable to various brake setting positions by means of a crank pin 14, the said pin being shown as having five operative positions. A 100

With the above and other considerations in mind, it is proposed, in accordance with this invention, to provide means whereby the effect of variation in the thickness of the car wheels will be minimized, in order to permit a relatively close adjustment of the brake shoe pressure to the weight of the car in question, regardless of such variations in car wheel thickness as occur in practice. More specifically stated it is proposed to press the brake shoes against the car wheels by compound spring means arranged so that different springs are initiated with action at different settings of the retarder, and in the specific embodiment described below, two such springs are used whereby to give a brake shoe pressure curve, plotted as a function of relative movement between the brake shoe and its actuator, having two relatively flat straight

suitable prime mover, preferable an electric motor, is contained in the casing 15, and is energized through a contact arm 16 and contacts 16', by means of an arm 17, the various contacts 16' corresponding to the various operative positions of the crank pin 14.

It is immaterial as far as the present invention is concerned as to how the crank pin 14 is operated to the various positions, p^0 , p^1 , p^2 , p^3 and p^4 , by suitable electrically operated means, it may be pointed out at this time that the casing 15 in practice preferably includes a suitable electric motor, and suitable circuit controlling means assuming a position depending on the position of the crank pin 14; which circuit controller is connected in a circuit arrangement which includes a plurality of branch circuits in multiple of which all of these branch circuits are completed within the casing 15 except one branch circuit thereof, and each of these branch circuits is such that if current is permitted to flow therein in response to movement of the lever 17 the motor is operated in a direction so as to open the branch circuit in question and close the branch circuit which was previously open. In other words, the control mechanism for the motor in casing 15 is such that the motor will operate the wheel containing crank pin 14 in a direction corresponding to the direction in which the lever 17 has been moved and will operate this motor until the crank pin has assumed a position corresponding to that of the lever 17. These features are somewhat more specifically illustrated and described in the co-pending application above referred to.

The lugs 4' and 5' are each connected to the brake bars 4 and 5, respectively by means which is the same in each case and hence a description of one will serve for all.

Referring more particularly to Fig. 3, the lug 5' on the actuating bar 5, is connected to the brake bar 3, by a stem 18, having a head 19 thereon which is pivoted to the member 3 by a pin 20. The other end of the stem 18 is received in an adjustable manner in an internal bore of an externally threaded screw 21, slidably received in the lug 5', and furnished with a bearing plate 22 and lock nuts 23. Slidably carried on the screw 21, is an annular washer 24, and a follower 25, the follower being externally threaded and receiving a threaded nut 26 adapted to bear in a socket 27 in the lug 5'. Bearing against the inner end of the screw 21, is an annular washer 28 which is slidable on the pin 18 and serves as an abutment for one end of an inner spring 29, the other end of which bears against a face member 30 on the member 19. Surrounding the inner spring 29 is an outer spring 31, bearing at one end against the same face member 30, and at the other end against the member 24. The member 24 has a pro-

jected rim 24' arranged in line with the annular washer 28.

The springs 29 and 31 are initially tensioned between their abutment members so as to contain a trapped tension, whereby, as soon as they are brought into play, they immediately exert a very considerable force, the amount depending upon the amount of initial tension in the springs.

The arrangement of parts described, permits independent adjustment of the initial tension of the springs 29 and 31, and of the distance between the brake shoe and the lug 5'. For adjusting the initial tension of the outer springs 31, the washer 24 and the follower 25 are adjusted inwardly or outwardly as the case may be, while for adjusting the initial tension of the inner spring the screw 21, together with the washer 28, is threaded inwardly or outwardly according to the result desired. For adjusting the position of the brake shoe relative to the lug 5', the lock nuts 23 can be adjusted along the screw 21, and in combination with the bearing plate 22, accomplish the desired result.

It should be readily understood from the above described structure, that operation of the crank pin 14 operating through the pitman 13 the lever 12 and rod 11 and the bar 10, will rock the lever 6 and thereby move the lugs 4' in one direction at right angles to the rails 1, while at the same time moving the lugs 5' in the opposite direction. Referring again more particularly to Fig. 3 it will be seen that movement of a lug, such for example as 5', will slide the members 26, 25 and 24 to the left against the tension of outer spring 31, and thereby exert this spring tension against the brake shoe in question, the pressure being dependent, at the initial point, on the trapped tension in the spring, and beyond that point, on the amount of movement between the lug and the brake shoe.

After a given amount of movement of the washer 24, in the case illustrated a movement equal to the distance between the rim 24' and the annular washer 28, the inner spring 29 is brought into initial action and from this point on, further relative movement between the lug 5' and the brake shoe, will operate to compress both of the springs and build up the pressure exerted by the brake shoes against the car wheels in accordance with the extent of movement of the lug 5' beyond this point.

The variation in brake shoe pressure corresponding to relative movement between brake shoe and actuating member, has been shown in the curve in Fig. 4, from which it will be seen that the first, and relatively flat part 32 of the curve corresponds to the pressure exerted by the outer spring 31 only, the upper and relatively steep part 33, of the curve corresponds to the pressures exerted by the two springs 29 and 31 in combina-

tion, and the vertical portions 35 and 34 represent the initial tensions of the inner and outer springs 29 and 31 respectively.

On the curve of Fig. 4, a plurality of operative positions for the crank pin 14 of Fig. 1 have been indicated by characters p^0 , p^1 , p^2 . It should be noted that the thickness of the car wheel being acted on will vary the pressure exerted by the brake shoes for a given setting of the retarder and with the machine set, for instance, at the point p^2 , for a normal width car wheel, should a wheel of greater thickness be operated on, the pressure would rise and the retarder would operate in a portion of the curve beyond the point p^2 , whereas if the wheel were thinner than normal, it would operate at a point in front of the point p^2 . In practice however, the variation from normal width is generally towards an increased thickness, and since, by having the vertical part 35 of the curve occur just in front of one operative position, namely p^3 , a wheel which is thicker than normal, operated on when the retarder is set at position p^3 , will shift the working point beyond the point p^3 , and hence will not vary the pressure from the desired one, to as great an extent, as if the part 35 of the curve were just beyond p^3 .

Should it be found however, that the variation from the normal wheel thickness, is towards a thinner wheel, then the pressure curve would be arranged so that the vertical portion 35 thereof would occur just beyond an operative position such for instance as p^2 , so that, as in the case before considered, the variation in the wheel thickness would not change the working point of the car retarder from one zone to the other. This has been illustrated graphically in Fig. 5 of the drawings.

If the wheel thickness varies on either side of normal, then the vertical part 35 of the curve would be placed midway between two settings, such as p^2 and p^3 of the retarder, as graphically shown in Fig. 6. The construction described gives a retarder operating along a pressure curve having two zones, a rather flat, and a comparatively steep zone, and thus, for light cars, its operation is in the flat zone where variation in wheel thickness will not change the pressure enough to cause the light car to ride upon the retarder, and for heavy cars such trouble is not experienced from ordinary brake shoe pressures.

From a consideration of the above it will be seen that a retarder has been produced, in which the pressures of the brake shoes vary according to a curve having an upper and steep zone, and a lower and flat zone, connected by a vertical portion, the curve being arranged relative to the operative positions of the retarder so that the usual variation in thickness of car wheels from the normal will

not shift the working position on the curve from one zone to the other. Thus the variation in thickness of the car wheels will merely shift the working point along one or the other of the uniform portions of the curve occurring in the two zones, and hence will not operate to suddenly and very greatly vary the actual pressure exerted, from the ideal pressure corresponding to the weight of the car to be retarded. At the same time, by having two separate zones in the curve, connected by a vertical portion, it is possible to build up a very high braking pressure, by working in the high pressure zone, without any necessity for an unduly large movement between the brake shoe and the actuating bar, which, of course, is desirable from a mechanical point of view.

Coil springs inherently have substantially a straight line characteristic, that is, the pressure with which a spring is compressed varies directly with the extent of deformation. By reason of the fact that the trouble of cars riding out at the top between brake shoes is experienced principally for light cars it is found expedient to have the pressure-deformation characteristic much steeper for the heavy cars and higher pressures than for the light cars and lower pressures. Since it is impossible to design a single and simple spring having a pressure-deformation characteristic such as just explained, applicant has designed a compound spring arrangement which has a pressure-deformation which approaches the characteristic just mentioned. In other words, the car retarder embodying the present invention includes spring mechanism which has an upturned pressure-deformation characteristic as compared with a straight line pressure-deformation characteristic as is true of a simple coil spring.

The initial tension of the two springs 29 and 31, can of course be adjusted in accordance with the operating conditions to be met, as can also the strength of the springs employed. Merely by way of example, it is noted that in one case it was found best to employ an outer spring having $\frac{1}{8}$ " initial compression, and a strength of 1000 pounds per $\frac{1}{8}$ " compression, with an inner spring 115 having $\frac{1}{2}$ " initial compression and a strength of 1000 pounds per $\frac{1}{8}$ " compression.

The above rather specific description of one form of the present invention is given solely by way of illustration, and is not intended, in any manner whatsoever, in a limiting sense. Obviously, the invention can assume many different physical forms, and is susceptible of numerous modifications, and all such forms and modifications are intended to be included in this application, as come within the scope of the appended claims.

Having described my invention, I now claim:—

1. In a car retarder of the type engaging the wheels of a passing car, a brake shoe, a shoe actuator, means slidably inter-connecting the shoe and actuator, a plurality of initially tensioned springs carried on said means between the shoe and actuator, the springs being arranged to initiate a relative moving effort on the shoe and actuator at different relative positions of said shoe and actuator.
2. In a car retarder of the type engaging the wheels of passing cars, a brake shoe arranged to engage the wheel of a passing car, a shoe actuator, and multiple spring positioned between the shoe and its actuator of which each spring has trapped pressure and of which one spring is not further compressed until the other spring has been deformed to a predetermined extent.
3. In a car retarder of the type engaging the sides of the wheels of passing cars, a brake shoe arranged to engage the wheel of a passing car, a shoe actuator, and multiple initially tensioned springs positioned between the shoe and its actuator of which one spring is not further compressed until another spring has been deformed to a predetermined extent.
4. In a car retarder of the type engaging the sides of the wheels of passing cars, a brake shoe arranged to engage the wheel of a passing car, a shoe actuator, multiple initially tensioned springs positioned between the shoe and its actuator and arranged to be brought into action at different positions of the actuator with respect to the shoe, and means for independently adjusting the initial tension of the springs.
5. In a car retarder of the type engaging the wheels of a passing car, a brake shoe, a shoe actuator, means slidably inter-connecting the shoe and actuator, and a plurality of initially tensioned springs arranged in multiple carried by said means between the shoe and actuator and arranged to be brought into action at different positions of the actuator with respect to the shoe.

In testimony whereof I affix my signature.
